(57) **CLAIM**

The ornamental design for a lottery terminal device as shown and described.

DESCRIPTION

FIG. 1 is a front perspective view of a lottery terminal device of my new design.

FIG. 2 is a front view of the lottery terminal device of FIG. 1.

FIG. 3 is a rear view of the lottery terminal device of FIG. 1.

FIG. 4 is a left side view of the lottery terminal device of FIG. 1, the right side view being a mirror image thereof.

FIG. 5 is a top view of the lottery terminal device of FIG. 1; and,

FIG. 6 is a bottom view of the lottery terminal device of FIG. 1.

The dashed broken lines in the drawings illustrate portions of the lottery terminal device that form no part of the claimed design.

1 Claim, 6 Drawing Sheets
